GIRDLE

Harry Steiner, New York, N. Y., assignor to Corde
De Parie Corset Co., Inc., Brooklyn, N. Y., a corporation

Application March 24, 1952, Serial No. 19,025

Term of patent 14 years

(Cl. D20—2)

To all whom it may concern:

Be it known that I, Harry Steiner, a citizen of the United States of America and a resident of the city of New York, in the county of Kings and State of New York, have invented a new, original, and ornamental Design for a Girdle, of which the following is a specification, reference being had to the accompanying drawing, forming a part thereof.

Fig. 1 is a front view of a girdle, showing my new design; and

Fig. 2 is a rear view thereof.

The garter portions of the girdle have been broken away for convenience of illustration.

I claim:

The ornamental design for a girdle, substantially as shown and described.

HARRY STEINER.
